WENDELIN P. SENG, OF CHICAGO, ILLINOIS.

TELLTALE AND SWITCH FOR REAR SIGNAL-LIGHTS FOR AUTOMOBILES.

1,216,370.

Specification of Letters Patent. Patented Feb. 20, 1917.

Application filed December 24, 1915. Serial No. 68,573.

To all whom it may concern:

Be it known that I, WENDELIN P. SENG, a citizen of the United States, residing at Chicago, in the county of Cook and State of Illinois, have invented a new and useful Telltale and Switch for Rear Signal-Lights for Automobiles, of which the following is a specification.

My invention relates to a new and improved switch for the operation of the rear signal lights of automobiles whereby the driver may indicate to the drivers of those automobiles following his intention to either stop or turn at a crossing.

Heretofore, in the use of such rear signals, the driver or operator of the automobile employing the same could never be positive, when he operated the signal switch, that the signal-light was actually lighted, and in some instances such has been found to be the case, by reason of burned out lamps, interference with the circuit, &c.

By my invention, however, I obviate this disadvantage and danger, by arranging a tell-tale lamp or light within the view of the driver-operator, so that he can, by a glance and without leaving his seat, unmistakably see when he throws the switch, whether the signal-lamp is lighted.

With such general objects in view, the invention consists in arranging the signal-lamp switch in a convenient manner and preferably immediately under the steering-wheel and in clear view of the driver and in connecting the same with a tell-tale lamp arranged in circuit with the signal-lamps and therefore designed to indicate when the same are not lighted.

Referring to the drawing—

Figure 1 is an elevation of a fragment of a steering-wheel and its post, employed in an automobile, a combined tell-tale and switch being applied to the latter;

Fig. 2 is a longitudinal sectional view of the tubular housing, preferably employed, and in which is located the switch and tell-tale, the switch and tell-tale being shown in elevation; and,

Fig. 3 is a detail in elevation of the switch, parts shown in section, and illustrating the same connected up with the usual signal lights and operating battery.

Similar numerals of reference indicate similar parts in all the figures of the drawing.

In carrying out my invention, I prefer-

ably employ a tubular housing 1, and mount the same on the steering-post 2, immediately below the steering-wheel 3, of an automobile, whereby not only is the hereinafter-described switch within easy reach of the hand of the driver while operating the wheel, but the housing itself is in full view of the driver's eye. Bayonet-slots 4 (see dotted lines Fig. 2), may be formed in the end of the housing, and the latter closed by a cap or cover 5, from which short studs 6 may project into said slots, whereby the cover is readily removable.

Immediately in rear of the cover the front end of the tubular housing is occupied by an insulating disk or plug 7, from which may radiate short studs 8, removably engaging bayonet-slots 9, whereby said plug and the parts carried thereby may be readily removed.

Upon the rear face of the insulating disk or plug 7, is pivotally mounted, by a screw 10, at one side of the center of the disk or plug, a segmentally shaped switch-plate 11, adapted to oscillate to either side of its pivot. This switch-plate is provided with an operating-handle 12, which extends radially and through a slot 13 in the housing and cap to a point immediately adjacent the steering-wheel 3. It is also provided at opposite sides of its pivot 10 with the radial contact shoulders 14 and 15.

At opposite sides of the center of the insulating disk or plug are located stationary contacts 16 and 17, having their inner ends bent at an angle to form narrow contact-flanges 16^a and 17^a, respectively, which flanges are in annular alinement with the shoulders 14 and 15, respectively. That is to say, by moving the switch in one direction, in this instance, to the left, the contact-shoulder 14 thereof will contact with the contact flange 16^a and by moving the switch to the right, the contact-shoulder 15 thereof will contact with the contact flange 17^a. The switch may be held in its neutral or inoperative position by means of a small spring-pressed detent 18, engaging with a corresponding counter-sink 19 formed in the inner side of the switch.

20 designates a small electric lamp, which I term the tell-tale. It is mounted in any convenient manner, but preferably as herein shown, on the insulating disk or plug 7, and immediately in line with a small orifice or sight-opening 21, formed in the upper side

of the tubular housing in direct line with the vision of the driver or at any other convenient point.

In the present instance, the lamp is removably mounted in a tubular socket 22, having a bayonet-slot 23, for engaging a pin 24 projecting from the side of the lamp, the socket itself being supported on the rear face of the insulating disk or plug by means of a leg 25, secured in position by means of a screw 26, passed through the inner flanged end of the leg and into said disk or plug.

27 and 28 indicate two contact-arms, preferably formed of spring material. The arm 27, leads from the switch-plate, being electrically secured to the same by means of the screw 10, while the arm 28 leads from and is held in position, preferably under the inner bent end of the leg 25, by means of the screw 26. The outer ends of these arms, it will be understood, are laterally bent and extend into the paths of the electric-terminals of the lamp, and therefore lie within the socket 23.

25 To illustrate the application of the invention, I have shown in connection with Fig. 3, the conventional form of rear signal, the same being designated as 29. This includes the usual transparencies upon one of which, 30 designated as 30, appears an arrow pointing to the left, and above the same, the word "Turn," so that when illuminated by the lighting of the lamp therein, the driver indicates that he is about to turn to the left. 35 The companion transparency, 31, carries the word "Stop," and when illuminated indicates that the driver is about to stop, these signals being used for the benefit of those drivers following, whereby to prevent rear-end collisions. I have also illustrated the source of electrical energy—a battery 32. The lamps of the two signals 30 and 31, are connected by a conductor 33, the same being common to both, and leading to one pole of 40 the battery 32. The remaining conductor 34 leads from the other pole of the battery, and is connected to the binding-screw 26. Conductors 37 and 38, lead respectively from the binding-screws 39 and 40, employed for 45 securing the contacts 16 and 17, to the insulating disk or plug, and to the signal-lamps within the transparencies. It will be obvious that by moving the switch to the left it will close the circuit through the conductors 37, 34 and 33, and thus illuminate the signal-lamp in rear of the transparency showing the arrow and the word "Turn." Moving the switch to the right, will close the circuit through the conductors 38, 33, and 50 55 60 65

34, and illuminate the signal-lamp in rear of the transparency showing the word "Stop." In either instance, however, there will be included in the circuit the tell-tale lamp 20, which will not light unless the rear signal-lamps light, and hence, by observing the

condition of this tell-tale lamp through the sight-opening 21, the driver will know at a glance, after throwing his switch, whether the signal-lamp thus connected up is doing its duty and the rear signal flashed to those drivers following. If, after throwing the switch, the tell-tale lamp does not light, it is positive evidence there is a break in the circuit and that therefore no signal is displayed at the rear.

70 75 It will be obvious that, by multiplying the circuits and contacts, the usual tail-light may be observed, but the invention is primarily intended for use in connection with the rear signal-lights, and for the purpose of reducing rear-end collisions as are often caused by the stopping or turning of automobiles without adequate warning to those behind.

80 85 90 By mounting the insulating disk or plug removably in the housing, all of the parts, including the lamp 20, may be instantly removed, inspected, and repaired if necessary. I do not, however, limit the invention to the details herein shown and described, as I have only shown and described what I consider best for the accomplishment of the purposes in view.

95 Having described my invention, what I claim, is:

1. A switch for the signal-lights of automobiles and the like, the same comprising a housing consisting of a tubular body-portion open at one end and a closure for said end, said housing having a sight-opening, a plug within the housing and removable from the open end of the same when the closure has been removed, a movable switch carried by the plug and removable therewith and having its handle projecting through and beyond a slot in the housing, electrical contacts carried by the plug and arranged in the path of the movable switch and each adapted to be in circuit with a signal-light, a tell-tale lamp carried by and removable with the plug and adapted to be in circuit with each of the signal-lights, and a connection between said tell-tale lamp and the switch.

100 105 110 115 120 125 130 2. A switch for the signal-lights of automobiles and the like, the same comprising a tubular housing provided with means for attaching it to the steering-post of an automobile or other object and with a sight-opening, a plug removably mounted in the housing, a switch-lever mounted to oscillate upon the plug and having its operating handle projecting through and beyond a slot formed in the housing, electrical contacts located on the plug at opposite sides of the switch-lever and in the path thereof and each adapted to be in circuit with a rear signal-light, a tell-tale lamp located on the plug adjacent the sight-opening of the housing and adapted to be in circuit with

each of the signal-lights, a connection between the tell-tale lamp and the switch-lever, and a removable cap or closure for the tubular housing.

5. A switch for the signal-lights of automobiles and the like, the same comprising a tubular housing having a sight-opening and means for attaching to the steering-post of an automobile or other object, an insulating plug removably mounted within the tubular housing, means for securing the same temporarily in position therein, a removable cap for the end of the housing, means for temporarily locking the same, a signal-light operating switch carried by the plug, and a tell-tale lamp in circuit with the switch and signal-lights and carried by the plug, whereby the switch and tell-tale lamp may be simultaneously removed with the plug from 20 the housing.

4. A switch for the signal-lights of automobiles and the like, the same comprising a tubular housing having a sight-opening, a removable cap or cover and means for locking the same in position on the end of the housing, an insulating plug removably secured in the housing, an oscillatory switch pivoted on the plug and having its operating-handle extending through and beyond 30 a slot formed in the housing, opposite electrical contacts secured to the plug at opposite sides of and in the path of the switch and each adapted to be in circuit with a signal-light, an intermediate standard secured to the plug, a socket carried by the standard, a tell-tale lamp within the socket adjacent the sight-opening of the housing;

an electrical conducting-arm extending from the pivot of the switch and terminating in contact with one of the contacts of the tell-tale lamp, and a similar arm contacting with the remaining contact of said lamp and connected to the base of the intermediate standard and adapted to be in circuit with each of the signal-lights. 40

5. A switch for the signal-lights of automobiles and the like, the same comprising a housing having a sight-opening, an insulating plug seated in the housing, an oscillatory switch-lever pivoted on the plug, 50 and having its operating-handle extending through and beyond a slot formed in the housing, electrical contacts secured to the plug at opposite sides of and in the path of the switch-lever, each of said contacts being 55 adapted to be in circuit with a signal-light, an intermediate standard secured to the plug, a socket carried by the standard, a tell-tale lamp within the socket and adjacent the sight-opening of the housing, an electrical conducting arm extending from the switch to one of the contacts of the tell-tale lamp, and a similar arm leading to the remaining contact of the lamp, said latter arm being mounted on the plug and adapted 60 to be in circuit with each of said signal-lights. 65

In testimony whereof I have signed my name to this specification in the presence of two subscribing witnesses.
